US0D1054431S

(12) **United States Design Patent** (10) **Patent No.:** **US D1,054,431 S**
Fong et al. (45) **Date of Patent:** **** Dec. 17, 2024**

(54) **DISPLAY SCREEN OR PORTION THEREOF WITH GRAPHICAL USER INTERFACE**

(71) Applicant: **Everi Payments Inc.**, Austin, TX (US)

(72) Inventors: **Adam Fong**, Las Vegas, NV (US);
Steve Nguyen, Las Vegas, NV (US);
Shane Taylor, Austin, TX (US);
Brendan Shelly, Las Vegas, NV (US);
Vivek Ramachandran, Chennai (IN)

(73) Assignee: **Everi Payments Inc.**, Las Vegas, NV (US)

(**) Term: **15 Years**

(21) Appl. No.: **29/786,636**

(22) Filed: **Jun. 1, 2021**

(51) **LOC (14) Cl.** **14-04**
(52) **U.S. Cl.**

(57) **CLAIM**

The ornamental design for a display screen or portion thereof with graphical user interface as shown and described.

DESCRIPTION

The sole FIGURE is a front view of a display screen or portion thereof with graphical user interface showing the new invention.

The outer perimeter broken line rectangle shows a display screen or portion thereof that forms no part of the claimed design. All other broken lines in the figures show portions of the graphical user interface which form no part of the claimed design.
